OLIVER A. KRAEER, OF BARTLESVILLE, OKLAHOMA.

PUMP.

1,135,821.

Specification of Letters Patent. Patented Apr. 13, 1915.

Application filed August 1, 1913. Serial No. 782,509.

To all whom it may concern:

Be it known that I, OLIVER A. KRAEER, a citizen of the United States of America, and a resident of the city of Bartlesville, in the county of Washington and State of Oklahoma, have invented a new and useful improvement in pumps for use in deep wells in raising oil and other mineral fluids from great depths to the surface; and I hereby declare that the following is a full, clear, and exact description thereof, which will enable others skilled in the art to make use of the same, reference being had to the accompanying drawing, forming a part of this specification.

In the pumps now used in raising oil and other mineral fluids to the surface from great depths, the fluid in the working or pump-barrel passes through a valve in the sucker or piston directly into the shaft above the pump-barrel, and the sand and sediment in the fluid passes through the valve and around the sides of the sucker, having a tendency to wear out the valve-cups attached to the piston, necessitating—and especially in case of oil wells—the frequent pulling of the rods from the well for the purpose of replacing the worn-out valve-cups.

One of the purposes of this invention is to so arrange the parts of the pump that, instead of passing directly through a valve in the piston into main shaft above the pump-barrel, the fluid passes from the pump-barrel through a side-pipe or tube and back into the main shaft above the pump-barrel, thus preventing the sand and sediment in the fluid from passing around the sides of the piston and wearing out the valve-cups, thus saving their cost, the cost of pulling the rods from the well to replace the valve-cups, and the loss of time in extracting the fluid while the pump is being repaired.

In the pump described in this specification, the downward stroke forces the fluid into the side-pipe or tube from the pump-barrel, the piston pushing down upon the weight of the fluid in the shaft above, through the open valve G, the weight of the rods being sufficient to carry the piston down, and the weight of the fluid in the main shaft being neutralized by its pressure both above and below the piston on the downward stroke.

Another benefit accruing from this invention is that by the use of the sand-protector

described in this specification the working-barrel and piston is protected from the sand and sediment which necessarily settles down when the pump is shut down for any cause.

The accompanying drawings represent a central vertical section of the same, Figure 1 representing the lower and Fig. 2 the upper part of the pump; wherein:

A, represents the main shaft through which the fluid is drawn from the bottom to the top of the well.

B, represents the holes in the pipe below the pump-barrel through which the fluid enters the pipe.

C, represents the valve, opening upward, in the main shaft, in the bottom of the pump-barrel, through which the fluid enters the pump-barrel on the upward stroke of the piston, and which prevents the backward flow of the fluid.

D, represents a side-pipe or tube which opens into the pump-barrel, at E, any desired point above the valve C, and below the lowest point of the downward stroke of the piston in the pump-barrel, and at F, any convenient point in main shaft above pump-barrel.

G, represents the valve opening upward, at a convenient point in the side-pipe or tube D, which prevents the backward flow of the fluid.

H, represents the piston-rod, to the end of which is attached the piston, which extends from the piston in the pump-barrel, to the top of the well where the power is applied in the usual manner.

I, I', J, K, L, M and N represent the several parts of the piston, attached to the piston-rod. There is no valve or opening in the piston, and the parts are so arranged with two reversed series of valve-cups as to clean the pump-barrel on both the upward and downward strokes of the piston and to prevent the fluid and sand or sediment from passing through or around the same.

More particularly—I, represents the upper series of cups, composed of several valve-cups, adjusted on the piston in the usual manner, with the usual washers M between, the cups being turned upward to prevent the fluid from passing back into the pump-barrel.

I', represents the lower series of cups, composed of several valve-cups adjusted on the piston in the usual manner, with the usual washers M between, the cups being

faced downward to prevent the fluid in the pump-barrel from passing around the piston into the shaft above.

5 J, represents a steel washer adjusted on the piston between the two series of reversed valve-cups.

K, represents a steel washer fitting into the lower surface of the bottom valve-cup.

10 L, represents lock-nuts at the end of the piston-rod screwed up tight against K.

M, represents the usual washers used between the valve-cups.

15 N, represents the head of the piston, being an enlargement of the piston-rod, fitting into the upper surface of the top valve-cup, thus holding the parts of the piston firmly in place between it and the lock-nuts L.

20 The sand-protector is composed of two members: O, represents the lower member of the sand-protector, through which the piston-rod passes, composed of a pipe attached to a base Q, with a beveled lower surface resting on a beveled seat in the top of the working barrel which is a convenient point 25 above the piston and below the upper opening of the side-pipe into the main pipe at F, said member extending on the piston-rod for a convenient distance above the pump-barrel. P, represents the upper member of 30 the sand-protector, being an inverted pipe around the piston-rod, closed at the top, open at the bottom, securely attached to the piston-rod at the top and telescoping over the lower member of the sand-protector O.

35 Q, represents the base of the lower member O. It has a beveled lower surface and rests on a beveled seat, T, in the top of the pump-barrel above the piston and below the opening, F.

40 R, represents the horizontal groove around the outer surface of the base Q.

S, represents one or more springs attached in a collar, U, around the main pipe, which fit into the groove R, and hold the member 45 O in its place on the beveled seat T; but which flatten on the application of sufficient power and permit the pulling of the piston and sand-protector from the well.

T, represents a beveled seat in the top of 50 the pump-barrel on which the member O rests.

U, represents the collar around the main pipe, in which the springs S are set.

The operation of the pump is as follows: 55 Upon the upward stroke of the piston, the weight of the fluid above closes the valve G, the valve C opens, through which the fluid runs into the pump-barrel. On the downward stroke, the valve C closes, the valve G opens, and the fluid in the pump-barrel is forced through G, through the side-pipe or tube D, and into the main shaft A, at F. No power is needed on the downward stroke, the weight of the rods being sufficient to carry 60 the downward stroke; and the weight of the 65

fluid in the shaft above the pump-barrel being neutralized by its pressure on the piston both above and below. The side-pipe, D, is of sufficient length to prevent the settling therein of the sand and sediment contained in the fluid in the main pipe above the pump-barrel, allowing the same to settle on top of Q, the base of the lower member of the sand-protector and below the opening, F. The piston is adjusted in the pump-barrel so 70 that the lowest point of its stroke is high enough above the opening E, and low enough below the opening F, to constantly retain the same fluid immediately above and below the piston and allow the sand and sediment contained in the incoming fluid to pass around the pump-barrel and out at the mouth of the well. The lower member of the sand-protector is held in place on its beveled seat by the weight of the fluid in the pipe above and 75 by the springs, S. It is of sufficient length to permit the settling of sand or sediment on top of the base Q and below the bottom of the upper member P. The bottom of the upper member P is below the upper opening 80 F of side-pipe D, to prevent the sand and sediment contained in the incoming fluid from entering the pipe P. There is sufficient space between the piston-rod and the members O and P, and between the members O 85 and P, to permit the free passage of the fluid.

Where the well produces gas with the mineral fluid, it is probable that the gas will collect in the inverted pipe P, and form an 100 elastic cushion against which the upward stroke of the piston will work and thus lessen the amount of power required to carry the upward stroke of the piston.

With the pump described in this specification, a large per cent of the floating sand may be cleaned out of the well, dispensing to a large extent with the use of the bailer.

I claim as new and desire to secure by Letters Patent:

1. A combination in a pump consisting of: a pump-barrel containing a solid piston; a piston-rod extending from the pump-barrel to the top of the well, to the bottom of which the solid piston is attached; a sand-protector composed of two members, through which the piston rod passes, the upper member being a pipe around the piston-rod, closed and attached to the piston-rod at the top, open at the bottom and telescoping over the lower 115 member of the sand-protector, and the lower member being a pipe around the piston-rod, having a base with a beveled lower surface; a beveled seat in the top of the pump-barrel upon which the base of the lower member of 120 the sand-protector rests; with space between the piston-rod and the two members of the sand-protector and between the two members of the sand-protector; a side-pipe or tube opening into the lower part of the pump- 125 130

barrel and into the main pipe above the same; a valve opening upward in the bottom of the pump-barrel; a perforated intake pipe below the pump-barrel; and a valve opening upward in the side-pipe or tube.

5 2. A combination in a pump consisting of: a pump-barrel, containing a solid piston; a piston-rod extending from the pump-barrel to the top of the well to the bottom of which the solid piston is attached; a sand-protector, composed of two members, through which the piston-rod passes, the upper member being a pipe around the piston-rod, closed at the top, open at the bottom, attached to the piston-rod at the top, and telescoping over the lower member of the sand-protector; and the upper member of the sand-protector being a pipe around the piston-rod, closed at the top, open at the bottom, attached to the piston-rod at the top, and telescoping over the lower member of the sand-protector; and the lower member being a pipe around the piston-rod attached to a base with a beveled lower surface, with space between the piston-rod and the two members of the sand-protector and between the two members of the sand-protector; a beveled seat in the top of the pump-barrel on which the base of the lower member of the sand-protector rests; with a convenient distance between the bottom of the upper member of the sand-protector and the base of the lower member of the sand-protector; the diameter of the piston and sand-protector being such as to permit their removal from the tubing with the piston-rod; a side-pipe or tube opening into the lower part of the pump-barrel at a convenient distance below the lowest point of the downward stroke of the piston and above the valve in the bottom of the pump-barrel, and into the main pipe above the pump-barrel a convenient distance above the base of the lower member of the sand-protector and above the bottom of the upper member of the sand-protector; a valve opening upward in the bottom of the pump-barrel below the lower opening of the side-pipe or tube into the pump-barrel; a perforated intake-pipe below the pump-barrel; and a valve opening upward at a convenient point in the side-pipe or tube.

3. A combination in a pump consisting of: a pump-barrel containing a solid piston, composed of two series of reversed valve-cups, the upper series facing upward and the lower series facing downward, its head being an enlargement of the piston-rod fitting into the top valve-cup, washers between the valve-cups, a washer between the two series of reversed valve-cups, a washer fitting into the bottom valve-cup, and lock-nuts screwed on the bottom of the piston-rod tight against the washer fitting into the bottom valve-cup; a piston-rod extending from the pump-barrel to the top of the well, to the bottom of which the solid piston is attached; a sand-protector composed of two members through which the piston-rod passes, the lower member being a pipe

around the piston-rod, having a base with a beveled lower surface, with one or more springs attached in a collar around the main pipe and fitting into a horizontal groove around the outer surface of the base of the lower member of the sand-protector; and the upper member of the sand-protector being a pipe around the piston-rod, closed at the top, open at the bottom, attached to the piston-rod at the top, and telescoping over the lower member of the sand-protector, with space between the piston-rod and the two members of the sand-protector, and between the two members of the sand-protector; a beveled seat in the top of the pump-barrel on which the base of the lower member of the sand-protector rests; with a convenient distance between the base of the lower member of the sand-protector and the bottom of the upper member of the sand-protector; a side-pipe or tube opening into the lower part of the pump-barrel a convenient distance below the lowest point of the downward stroke of the piston and above the valve in the bottom of the pump-barrel, and into the main pipe above the pump-barrel a convenient distance above the base of the lower member of the sand-protector and above the bottom of the upper member of the sand-protector; a valve opening upward in the bottom of the pump-barrel below the lower opening of the side-pipe into the pump-barrel; a perforated intake-pipe below the pump-barrel; and a valve opening upward at a convenient point in the side-pipe or tube, substantially as described.

4. A sand-protector for the piston of a pump, consisting of two members through which the piston-rod passes, the lower member being a pipe around the piston-rod, attached to a base with a beveled lower surface; a beveled seat in the top of the pump-barrel, on which the base of the lower member rests, and the upper member being a pipe around the piston-rod, closed at the top, open at the bottom, attached to the piston-rod at the top and telescoping over the lower member of the sand-protector, with space between the piston-rod and the two members of the sand-protector.

5. A sand-protector for the piston of a pump, composed of two members through which the piston-rod passes, the lower member being a pipe around the piston-rod, having a base with a beveled lower surface, with one or more springs attached in a collar around the main pipe, fitting into a horizontal groove around the outer surface of the base of the lower member of the sand-protector; and the upper member being a pipe around the piston-rod, closed at the top, open at the bottom, attached to the piston-rod at the top and telescoping over the lower mem-

ber of the sand-protector, with space between the piston-rod and the two members of the sand-protector, and between the two members of the sand-protector; a beveled 5 seat in the top of the working-barrel on which the base of the lower member of the sand-protector rests; in combination with a pump-barrel containing a solid piston; a piston-rod extending from the pump-barrel to the top of the well, to the bottom of which a solid piston is attached; a side-pipe or tube opening into the lower part of the pump-barrel a convenient distance below the lowest point of the downward stroke of the 10 piston and into the main pipe a convenient distance above the base of the lower member of the sand-protector; a valve opening upward in the bottom of the pump-barrel; a perforated intake-pipe below; and a valve 15 opening upward in the side-pipe or tube.

6. A combination in a pump consisting of: a pump-barrel containing a solid piston composed of two series of reversed valve-cups adjusted on the bottom of the piston-rod, the upward series facing upward and the lower series facing downward, its head 20

being an enlargement of the piston-rod fitting into the top valve-cup; washers between the valve-cups; a washer between the two series of reversed valve-cups; a washer fitting in the lower valve-cup; and lock-nuts screwed on the bottom of the piston-rod tight against the washer fitting into the bottom valve-cup; a piston-rod extending from the pump-barrel to the top of the well, to the bottom 25 of which the solid piston is attached; a side-pipe or tube opening into the lower part of the pump-barrel below the lowest point of the downward stroke of the piston and into the main pipe above the pump-barrel; a valve opening upward in the bottom of the pump-barrel; a perforated intake-pipe below the pump-barrel; and a valve opening upward in the side-pipe or tube. 30

In witness whereof, I affix my signature 35 in the presence of two witnesses this 22 day of July, 1914.

OLIVER A. KRAEER.
